BASEBALL SCORE CARD

Arthur I. Katzif, St. Louis County, Mo., assignor to The Magic Score Card Co., St. Louis, Mo., a corporation of Missouri

Filed July 11, 1966, Ser. No. 3,025

Term of patent 14 years

(Cl. D34—5)

The dominant features of my design reside in the portions shown in full lines, said design being characterized by the combination on a scoreboard of a baseball box score pattern at diagonally opposed ends with a pad of foreshortened pages attached by equally spaced rings across the center of the scoreboard, all as shown.

I claim:

The ornamental design for a baseball score card, as shown and described.
